[57] CLAIM

The ornamental design for a countertop, gooseneck-style, optical scanner for use with point-of-sale register, as shown and described.

DESCRIPTION

FIG. 1 is a left side elevational view of a counter-top gooseneck-style optical scanner for use with point-of-sale register showing our new design;

FIG. 2 is an enlarged top plan view thereof;

FIG. 3 is an enlarged right side elevational view thereof;

FIG. 4 is an enlarged front elevational view thereof;

FIG. 5 is an enlarged rear elevational view thereof;

FIG. 6 is an enlarged bottom plan view thereof.

The point-of-sale register is shown in broken lines in FIG. 1 for illustrative purposes only and thus forms no part of the claimed design.

FIG. 1

FIG. 2
